United States Patent Office

Des. 183,478
Patented Sept. 9, 1958

183,478

CHAIR

Morton R. Cohen, Chicago, Ill.

Application February 12, 1958, Serial No. 49,613

Term of patent 14 years

(Cl. D15—1)

Fig. 2.

Fig. 1.

Fig. 1 is a perspective view of a chair, showing my new design;

Fig. 2 is a rear perspective view of the same;

Fig. 3 is a front elevational view of the same;

Fig. 4 is a side elevational view of the same; and

Fig. 5 is a perspective view of the frame of the chair with the seat and backrest omitted for convenience of illustration.

I claim:

The ornamental design for a chair, substantially as shown.
